[57] CLAIM

The ornamental design for an ice bucket with lid, as shown and described.

DESCRIPTION

FIG. 1 is a front elevational view of an ice bucket with lid showing my design, the lid shown partially raised, the opposite side being a mirror image;

FIG. 2 is a left side elevational view thereof, the opposite side being a mirror image;

FIG. 3 is a top plan view thereof; and

FIG. 4 is a sectional view thereof on the line 4-4 of FIG. 3.

Fig.1.

Fig.2.

Fig. 3.

Fig. 4.
